Application January 17, 1935, Serial No. 2,170

4 Claims. (Cl. 15—192)

This invention relates in general to brushes and methods of making them and more particularly to so-called full row brushes as contrasted with tufted or knotted brushes.

Heretofore, full row brushes have consisted of rows of bristles which have had one end dipped into a plastic composition such as vulcanized rubber and then secured in a metal ferrule or frame by rivets or nails passing through said ends of the rows of bristles and the ferrule, the ferrule being connected to a wooden head by nails or the like. Another form of full row brush is shown in Patent No. 1,642,974 where the rows of bristles after having been dipped in the plastic composition are clamped in channels in a metal plate which is secured to the head of the brush. These known methods and structures are complicated and expensive, requiring complex and expensive apparatus, machines and tools and large amounts of time and labor.

One object of the present invention is to provide a novel and improved full row brush which shall be simple and inexpensive in construction and can be manufactured at low cost.

Another object is to provide such a brush which shall be strong and durable wherein the bristles shall be firmly and directly connected to the back or head of the brush without the necessity for rivets or the like fastening members or specially formed complex holding plates.

Another object is to provide a novel and improved method of making a brush of this character, and particularly novel and improved method for assembling the rows of bristles and inserting them into the brush back, whereby a great saving in time and labor over known methods shall be possible.

Other objects are to provide novel and improved means for separably connecting a handle to the brush back; to provide a novel and improved structure whereby the brush can be made entirely of metal except the bristles and the handle; and to obtain other advantages and results as will be brought out by the following description.

Referring to the accompanying drawings in which corresponding and like parts are designated throughout the several views by the same reference characters,

Figure 1 is a transverse vertical sectional view through a brush showing the manner of assembling the parts in accordance with the invention.

Figure 2 is a similar view showing the completed brush.

Figure 3 is a horizontal sectional view on the line 3—3 of Figure 1.

Figure 4 is a bottom plan view of the brush back.

Figure 5 is an end elevation of the completed brush.

Figure 6 is a vertical longitudinal sectional view through the brush on the line 6—6 of Figure 2.

Figure 7 is a view similar to Figure 2 showing a modification of the method of forming a screw socket for the handle.

Figure 8 is a similar view showing the completed socket and a portion of the cooperating handle.

Figure 9 is a top plan view of the mold block used for making the socket and

Figure 10 is a transverse sectional view through a brush having another modification of the handle socket.

Specifically describing the illustrated embodiment of the invention, the brush includes a cup-like back A preferably formed of sheet metal and including a bottom 1 and an upstanding perimetral flange 2 which has an inturned edge 3. As shown, the brush back is generally rectangular in plan view and centrally of the back is formed a handle attaching boss 4 which has a handle-receiving opening 5. Obviously the back may be of other shapes, for example, round or oval.

In making the brush, an interiorly screw-threaded socket shell 6 having an outturned perimetral flange 7 is set on the inside of the bottom 1 of the back with the flange resting on the inside of the boss 4 and the socket aligned with the opening 5, and a liquid plastic composition, for example liquid rubber which may be hardened upon vulcanization, is placed in the back A as shown in Figure 2. Rows of bristles 9 are arranged within an annular ferrule 10 with one or more spacers 11, depending upon the type of brush, extending longitudinally of the ferrule and between the rows of bristles and inwardly of the ends of the bristles. The ferrule is preferably of approximately the same size as the open side of the back, and certain rows of bristles are disposed between the ferrule and the next adjacent spacers 11, while other rows are disposed between the spacers as shown in Figure 1. Preferably the spacers are at least partially inserted within the ferrule so as to firmly clamp the rows of bristles in position. If desired, the ends of the bristles may be dipped in liquid composition although this is not necessary. After the bristles and

spacers have been so arranged in the ferrule the ferrule is set upon the edge of the back and the bristles and spacers are forced into the back as by means of a knife blade or tool C inserted between the bristles and pressed against the tops of the spacers. The spacers and the ends of the bristles are thus embedded in the composition 8, the spacers squeezing the composition around the bristles. Preferably the spacers 11 are channel-shaped with their bases 12 adjacent the bottom of the brush back and openings 13 are formed in the bases of the spacers to permit the liquid composition to flow into the channels as shown in Figure 2. Thereafter, the plastic composition 15 may be vulcanized or hardened in any known manner. The ferrule 10 may be slipped from the opposite ends of the bristles any time after the bristles and spacers have been inserted into the composition.

When the plastic composition has become hardened the bristles and spacers are firmly embedded in the composition, and the block of composition is firmly held in the back by the inturned flange 3 in addition to the adhesive contact of the composition with the metal of the back. Also, the handle socket 6 is firmly secured in the back so that a handle D having a screw-threaded portion E corresponding to the socket 6 may be threaded into the socket. Preferably the handle has a shoulder F at the inner end of the threaded portion E to abut the outside of the bottom 1 of the back, whereby said bottom is clamped between the shoulder and the socket shell. With this construction, the handle, bottom of the back, the hardened composition 8 and the socket shell mutually reenforce each other to prevent bending of said bottom and cracking of the hardened composition.

A modification of the handle socket is shown in Figures 7 and 8 where the socket is formed by inserting a screw threaded mold plug 14 through the opening 5 in the back prior to placing of the plastic composition into the back, so that after hardening of the composition the mold block may be removed and leave a screw threaded socket 15 in the composition to receive the screw threaded handle 16. Preferably the mold block would be soaped before insertion into the composition so as to facilitate removal of the block after the composition has hardened. A further modification is shown in Figure 10 where the handle socket is shown in the form of a wooden bushing 17 inserted into the back and the composition like the socket E and having a screw threaded opening 18 to receive the handle.

It is desirable that the spacers 11 and back A be so proportioned in size that the bristles are firmly clamped between adjacent spacers and between the outer spacers and the flange 2 of the back to supplement the composition 8 in binding the bristles and spacers in the back. Furthermore, it is an important feature of the invention that the spacers are embedded in the composition so as to provide substantial reenforcement for the composition block and the back of the brush when the composition has hardened.

While we have shown and described the invention as embodied in certain details of construction,

it should be understood that the details of structure may be modified and changed without departing from the spirit or scope of the invention, and particularly the shape of the brush back and the spacers 11 may be widely modified within the spirit of the invention. Therefore, we do not desire to be understood as restricting ourselves in the construction and use of the invention except as required by the following claims when construed in light of the prior art.

Having thus described our invention, what we claim is:

1. A brush comprising a cup-like back having a bottom and an upstanding perimetral flange with an inturned edge, a plastic composition in the back, and a plurality of rows of bristles and spacers embedded in said composition, said spacers being channeled members with their bases adjacent said bottom of the back and their flanges projecting away from said bottom and having perforations in their bases through which said plastic composition extends into the channels, whereby the spacers are held in position in the back by said plastic composition, certain of said rows of bristles having their ends arranged between adjacent spacers while other rows are arranged between certain spacers and the flange of said back.

2. A brush comprising a cup-like sheet metal back having a bottom and an upstanding perimetral flange with an inturned edge, said bottom of the back having a handle receiving opening, an interiorly threaded socket member in said back in contact with said bottom and with its socket in register with said opening, bristles, a hardened plastic composition in said back embedding the ends of said bristles and said socket member, and a handle having a threaded end screwed into said socket through said opening and a shoulder abutting the outside of said bottom of the back whereby said bottom is clamped between the socket member and said shoulder on said handle, said hardened plastic composition, bottom and socket members mutually reenforcing each other.

3. A brush comprising a cup-like metal back having a bottom and an upstanding perimetral flange, said bottom having a handle receiving opening, a sheet metal interiorly threaded socket shell having an outturned perimetral flange mounted on the inside of said back with its socket registering with said opening, bristles, and a hardened plastic composition in said back embedding said bristles and said socket shell.

4. A brush comprising a cup-like back having a bottom and an upstanding perimetral flange with an inturned edge, a plastic composition in the back, and a plurality of rows of bristles and spacers embedded in said composition, said spacers having openings through which the composition extends whereby the spacers are held in position in the back solely by said plastic composition, certain of said rows of bristles having their ends arranged between adjacent spacers while other rows are arranged between certain spacers and the flange of the back.
